WRAP STRIPE ATTACHMENT FOR CIRCULAR
KNITTING MACHINES

Marvin R. Bryant, Hickory, N. C., assignor to
Elliott Knitting Mills, Inc., Hickory, N. C., a
corporation of North Carolina

Application January 28, 1949, Serial No. 73,361

12 Claims. (Cl. 66—54)

1

This invention relates to improvements in circular knitting machines and more especially to a method and mechanism for forming wrap stripes in knitted fabrics wherein two or more different colors of wrap yarn may be knitted in wales immediately adjacent each other, or, as a matter of fact, each of the wales of the knitted fabrics may have a separate wrap yarn knitted therein, if so desired.

In the case of such circular knitting machines as the Banner 8 step wrap stripe attachment machine and the 8 step "Argyle" attachment machine, which are manufactured by the Hemphill Company of Pawtucket, Rhode Island, it has heretofore been impossible for two side-by-side needles to pick up two different wrap yarns in knitting the same course.

It is therefore the primary object of this invention to provide means whereby the needle or needles for one color of wrap yarn may rise higher relative to the needle cylinder than the normal height of the needle or needles for another color of wrap yarn and to provide feed fingers of different lengths which are secured to the conventional wrapping head assembly of the knitting machine. The longer finger or fingers feed the wrap yarn to the needles which are disposed at the normal height and the shorter finger or fingers feed the wrap yarn to the needle or needles which rise higher than the other wrap needles.

Inasmuch as the mechanism required for bringing about this result is quite sensitive in its operation, vibration of the various parts of the machine must be held to a minimum.

It is therefore another object of this invention to provide a split cam plate, the cam plates heretofore having been of one piece, whereby that portion of the cam plate which carries the selector unit, and the cam bars which control the jacks and the associated needles for the wrapping operation, is fixedly mounted on the frame of the machine and that part of the cam plate which carries the conventional stitch cam block assembly is mounted for vertical movement relative to the fixed portion of the cam plate, it being a well known fact that the stitch cam block must move vertically to apply proper variable tension to the knitted courses.

Heretofore, when the cam plate has all been of one piece, it has been necessary to raise and lower the entire cam plate in maintaining a proper tension on the knitted courses. This not only moved the selector fingers or cam bars of the selector unit out of alinement with the selector cams on the pattern drum adjacent the selector

2

unit, which often changes the pattern unintentionally, but also, of necessity, limited the range of vertical movement of the stitch cam block assembly, due to the fact that the one piece cam plate is mounted off-center on its raising and lowering means and, consequently, would bind on the needle cylinder if raised or lowered beyond certain limits.

Therefore, means are provided whereby the 10 stitch cam block will respond instantly to changes in the tension or fashion cams, which is particularly important in knitting the looper courses after which the looper round is knitted in the final knitting operation of a stocking blank 15 and such means permit the use of heavier yarns than have heretofore been possible due to the increased range of movement of the stitch cam block.

Some of the objects of the invention, having 20 been stated, other objects will appear as the description proceeds, when taken in connection with the accompanying drawings, in which

Figure 25 is a sectional plan view taken along the line 25-25 in Figure 24 and showing the wrap feed fingers mounted on the upper and lower disks but omitting the wrap yarns;

Figure 26 is a sectional plan view taken along the line 26-26 in Figure 24, showing the lower disk and associated guiding fingers but omitting the wrap yarns;

Figure 27 is an isometric view showing a particular set of selecting jacks for making the "Argyle" pattern shown in Figures 16 and 18;

Figure 28 is a view similar to Figure 24 but showing fewer wrapping fingers mounted on the wrap disks for knitting an "Argyle" pattern slightly different from that shown in Figures 16 and 18;

Figure 29 is a view similar to Figure 28 but showing the mechanism as each of the disks and accompanying wrap yarn guiding fingers have been rotated to a different position;

Figure 30 is a sectional plan view being taken substantially along the line 30-30 in Figure 29 but omitting the wrap yarns;

Figure 31 is a schematic isometric view showing the relationship between the conventional wrapping head and some of the wrap needles and other of the parts associated therewith;

Figure 32 is a schematic top plan view showing the relative positions of the wrap disk, the needle circle and the throat gap.

General description

The general construction of the knitting machine with which this invention is adapted to be associated comprises a base plate 10 (Figure 1), a driven needle cylinder 11, a sinker head 12, a cap 13, and a latch ring 14. The latch ring is pivotally swung in the conventional manner and carries the conventional yarn feed fingers generally indicated at 15 and through which the body yarn 16 as well as plating yarns, and reinforcing yarns are fed in a conventional manner.

The yarn feed fingers 15 are adapted to be controlled from a main cam drum 20 fixedly mounted on a driven cam shaft 21. The usual cams for controlling the yarn feed fingers 15 and many of the intervening connections are not shown since they are well known and are not materially different from those in the usual types of Banner machines.

It might be stated that although a Banner machine is generally referred to in this specification, it is equally possible for the principles of this invention to be applied to various other machines, it being evident to those skilled in the art that some modifications are required if it is desired to apply such principles to another type of machine.

A conventional stitch cam block 24 is slidable in the usual supports on a cam plate 25 and carries a conventional center cam, stitch cam and other cams, all of which will be later described in detail. The cam plate 25 is a part of the split cam plate as will be later described.

Referring to Figures 13, 14, 19 and 20, the cylinder 11 has latch needles broadly designated at 30 working in the usual needle slots beneath which are individual selecting jacks broadly designated at 31. The needles 30 have butts 32 and are usually divided into long and short butt groups for the well known purpose of separating instep and heel needles during the knitting of a heel and toe. Each of the jacks 31 has a plurality of removable butts 34 for pattern purposes. These butts may be removed by breaking or any other desired method. Above these removable pattern butts is a butt 35 for the purpose of raising jacks and associated needles by a dividing cam, not shown, for knitting the ribbed elastic top portion of a stocking. A further description relating to the ribbed elastic top is deemed unnecessary and the butt 35 is merely shown because it is a usual part of jacks of this type. Some of the jacks 31 have an outwardly projecting butt 36 at the lower end thereof which is adapted to engage cams which are a part of the present invention and will be more fully described later in this specification. Each jack 31 on that side of the needle cylinder which knits the sole of the stocking has a shorter butt 37 relative to the butt 35 for the purpose of engag-

ing a plain sole cam to return partially selected jacks to original position for cutting out the pattern on short butt needles during knitting between the ends of the wrap stripe and when the heel begins. Figures 13 and 14 show a master butt 40 on the jacks 31 which has been omitted from the jacks in Figures 19 and 20, and this master butt 40 engages a cam to be later described which is essentially a part of the selecting means.

The function of the butts 34, 36, 37 and 40 of the jacks 31 as well as the various cams and selector elements which function upon these jacks will be later described in detail.

In making the pattern shown in Figures 15 and 17, the wrapping is accomplished by any satisfactory wrapping mechanism, but preferably a single disk wrapping means of the Banner type such as is disclosed in U. S. Patent No. 1,702,608 is to be employed. The wrap mechanism as shown in said patent is employed exactly as described with the exception of the feed fingers, to be presently described, which are a part of this invention and through which the wrap yarns pass rather than through the guiding eyelets 116 in said patent.

In view of said patent, the mechanism relating to the wrapping mechanism need not be described in detail and the showing includes a vertically disposed spindle 45 (Figure 1) eccentrically mounted with respect to the needle cylinder 11 and rotatable at a 1 to 1 ratio therewith. This spindle 45 carries at its lower end a disk 46 (Figures 22 and 23) having a plurality of pairs of wrap thread guiding fingers secured thereto as by screws 48, each pair of which consists of a long finger 47 and a short finger 47a. These fingers are spaced about the periphery of the disk 46 for guiding individual wrap yarns, supplies of which are mounted at the usual position at the upper end of this eccentrically rotating assembly. Except when being specifically referred to, the wrap yarns will be generally designated at 50. Suitable tension means such as shown in Patent No. 1,702,608 are employed in the present invention.

The machine is provided with a suitable wrap horn 49 along which the wrap yarns around the needles move to the knitting point.

Referring to Figure 22, it may be noted that the lower ends of wrap fingers 47a are disposed at a higher horizontal plane than the lower ends of the wrap fingers 47 and this is accomplished by securing the inwardly bent portions of the fingers 47 to the bottom of the disk 46 and securing the inwardly bent portions of the fingers 47a to the top of the disk 46, the fingers 47 and 47a actually being of the same length. It is thus seen that the needles 39 that are raised to the normal height for a wrapping operation, by means to be later described, will receive the wrap yarn 50 from the wrap finger 47 in Figure 22 and the needles 36, which are elevated to a higher position than the normal wrap needles are elevated, will receive the wrap yarn 50 from the wrap finger 47a, whose lower end is disposed at a higher elevation than the lower end of the wrap finger 47 shown in Figures 22 and 31.

Although Figures 22 and 31 show but one pair of wrap fingers, it is manifest that many more pairs of fingers would be required to make the pattern shown in Figure 15. In this instance a disk substantially larger than normal would be required (such as is shown in Figure 23) in or-

der to accommodate the required number of wrapping fingers 47 and 47a.

Now, referring to Figures 1 to 7 inclusive, the conventional selecting means for determining the wrap pattern will be described. The base plate 10 has a circular portion 55 which has an extension 56 on which is mounted a post 57 (Figure 3) which is slidable within a supporting arm or bracket 58 (Figure 3) which is capable of being swung about a pivot 61 on the extension of the base 55 and is suitably restrained by a shoulder screw 62 working within a slot 63 adjacent its other end. A spring 64 is connected to the swinging bracket 58 and to a fixed part of the machine and tends to draw the pattern drum assembly inwardly to a limit determined by the adjustable stop screw 65. Means for swinging the bracket 58 as well as the structure relating to the pattern drum assembly, to be later described, is clearly shown and described in U. S. Patent No. 2,244,379. That mechanism need not be described in detail here and the showing includes a pattern drum 70 which is rotatably mounted on the post 57 and is restrained by the usual friction elements 71 disposed at the upper end of the post 57.

The lower part of the pattern drum 70 has a ratchet wheel 72 integral therewith, there being a connection between the same and other driven parts of the machine, and by means of which the pattern drum 70 is rotated in step by step relation. The pattern drum 70 has a plurality of pattern disks 75 thereon which are keyed to rotate with the pattern drum 70, these disks having removable butts 76, some of which are broken away and some of which are shown intact in Figures 2, 3 and 5.

The selections determined by the butts 76 are imparted, through a series of slideable plungers or selector fingers 77, or other suitable means, to the butts 34 of the jacks 31 (Figures 19, 20, 21 and 13). These selector fingers 77 are arranged to be spaced properly for engagement of their inner beveled ends beneath the butts 34 of the jacks 31 at the respective heights of the selector fingers. The selector fingers 77 are urged outwardly by individual springs 80 (Figures 6 and 7) but are pushed inwardly when they are engaged by butts 76 of the selector drum 70. If in an inward position, a selector finger will engage any butts 34 at its level and will raise them, as shown in Figure 12, so that the master butt 40 will engage and ride up a cam 82 (Figures 12 and 13).

It will be noted in Figure 12 that those jacks 31 having the master butt 40 thereon do not have the outwardly projecting butts 36 at the lower ends thereof and, conversely, the jacks 31 having the outwardly projecting butts 36 at the lower ends thereof do not have the master butts 40 and it is only the jacks 31 having the master butts 40 integral therewith which will ride up on the cam 82 in the manner heretofore described. The purpose of the outwardly projecting butts 36 at the lower ends of the jacks 31 and the elimination of the master butts 40, on the jacks 31, will be later described in detail inasmuch as it is an important part of the invention.

Above the group of selector fingers or plungers 77 is a single plunger 83 (Figure 7) having a cam 84 at its inner end. This plunger slides in the same supports 85 and 86 in which the selector fingers or plungers 77 slide and is held or urged inwardly by a spring 87. This cam 84 engages the butts 31 on the jacks 31 which are to be

found on the jacks under the sole group of needles only. This cam is projected inwardly at such times as patterning is to be discontinued from that group of needles; that is, in the high splice or double sole needles. The plunger 83 has a projection 87a (Figures 6 and 7) which is engaged by a toe portion 88 of a lever 90. This lever 90 is pivotally secured as at 91 to the bracket 86 which supports this portion of the selecting mechanism.

A link 92 connects the outer end of the lever 90 and projects downwardly through the circular base 55 to bear upon the main drum 20 in a conventional manner, or to be raised by certain cams, not shown, mounted thereon. When the link 92 is raised, the spring 87 will be allowed to draw the plunger 83 and its cam 84 inwardly so that the butts 37 may engage the same. When the link 92 is not in a raised position, conventional spring means, not shown, or its own weight will cause the same to move downwardly to thus hold the cam 84 outwardly and out of the path of the butts 37 on the jacks 31. When in butt engaging position, the cam 84 will immediately lower any jacks, having a butt 37 thereon, that have been raised by the selector fingers 77 before the butts 34 have a chance to ride up the cam 82. Thus in the making of plain sole, wrap stripe patterning may be continued through the instep but will not appear in the sole.

Split cam plate

Referring to Figures 1, 2, 3, 4, 5, 10 and 11, inclusive, the structure relating to the split cam plate is clearly shown. In Figure 10 it may be noted that the cam plate 25 is cut along the lines 100 and 101 thus leaving a fixed member or fixed cam plate 102. The parts 25 and 102 are shown separated in Figure 10; but when assembled on the machine their proximate edges abut against each other in a sliding fit. This fixed cam plate 102 has a conventional instep cam bracket 103 secured thereon, as by screws 104 and 104a, (Figure 5). Screw 104 is threadably embedded in a threaded hole 93 in the plate 102 and screw 104a slidably penetrates a hole 94 in the plate 102 and also slidably penetrates an ear of a conventional jack cam bracket holder 105, the lower surface of the ear being engaged by a post 106 and the lower end of which is welded to a plate 107 (Figures 5 and 11).

The aforesaid jack cam bracket holder 105 is an integral part of the unit in which the selector fingers 77 are mounted. The screw 104a, which slidably penetrates the ear of the jack cam bracket holder 105, is threadably embedded in the upper end of the post 106 to thus secure the instep cam bracket 103, the jack cam bracket holder assembly 105 and the fixed cam plate 102 disposed therebetween to the upper end of the post 106.

The jack cam bracket holder 105 has an ear 95 at the opposite side thereof in Figures 1, 3 and 4, the lower surface of which is engaged by a second post 108 and the lower end of which is welded to the plate 107 (Figure 11). The plate 107 is secured to the circular portion 55 of the base plate 10, as by screws 110, which also secure the extended portion 56 to the circular portion 55 of the base 10.

Conventional needle support cams 112 and 113 are secured to the fixed cam plate 102, as by screws 115 penetrating threaded holes 96 in cam plate 102 (Figures 2, 5, 10 and 12). Beneath that

portion of the cam 112 which is penetrated by the screws 115, is a screw 116 (Figures 2 and 5) the head of which is flush with the top surface of the fixed cam plate 102 and slidably penetrates hole 96, countersunk at its upper end. This screw 116 secures the fixed cam plate 102 to a third post 117 which is slidably penetrated by the screw 116 and the lower end of the screw 116 is threadably imbedded in a plate 118 secured as by screws 120 to the circular portion 55 of the base plate 10.

A conventional cam 125 is disposed above the juncture of the needle support cams 112 and 113 (Figure 12) and this cam is adjustably secured, as by a screw 126 (Figures 2 and 5) to a bracket 127 which is secured by two screws 97 to the cams 112 and 113.

Now, referring to Figures 2, 3, 5 and 12, the conventional group of cams constituting the so-called instep cam assembly will be described. These cams serve, upon going into reciprocatory knitting such as in the heel and toe, to raise the instep group of needles to an inactive position which they will retain until rotary knitting is resumed. There are three of these cams herein designated as an instep draw cam 130, an alining cam 131 and an instep raise cam 132 (Figure 5). Heretofore, the cams 130 and 131 have been made of a single curved member; however, by referring to Figures 12 and 13, it may be observed that the butts 32 of some of the needles 30 must pass between the cams 130 and 131 while these cams are in their lower position and as the butts 32 are raised and as the wrap yarns 50 are fed to the higher than normal corresponding wrap needles. Therefore, the cams 130 and 131 are joined together by an arcuate member 135 (Figure 2) out of the paths of the butts 32 to thus form an opening 136 between the arcuate member 135 and the needle cylinder 11 and it is through this opening 136 that the butts 32 of some of the needles 30 pass in picking up the wrap yarn. The cams 130, 131 and 132 are arranged to have vertical sliding movement in a conventional manner, the means for transmitting this vertical movement to the cams 130, 131 and 132 being clearly understood by those familiar with the art and a further description is not deemed necessary with the exception that the instep cam bracket 103 has a block 137 (Figure 2) mounted therein for vertical sliding movement and the cam 130 is secured to the same as by a screw 143 (Figure 12). The means for transmitting vertical movement to cams 130, 131, and 132 is set forth in U. S. Patent No. 2,244,870.

Referring to Figure 12, it may be observed that the cam blocks 112 and 113 have a groove 139 at their lower edges which is adapted to guide the jacks 31 having the butts 40 integral therewith and the groove 139 in the cam 113 forms a raise cam 141. Now, as the jacks 31, having the master butts 40 thereon, move from right to left in Figure 12, the cam 141 will raise the jacks 31 having the master butts 40 thereon in such a manner as to bring the butts 34 into alinement with the ends of the selector fingers 77. In the event that a particular selector finger is in the path of the butts 34 on the jacks 31, having the master butts 40 integral therewith, the master butt 40 will ride up the cam 82 in the manner heretofore described. In so doing, the butts 32 of the associated needles 30 will move along the path indicated by the dotted lines 143 and will be moved downwardly by the cam 125 and will then be raised upwardly by the cam 113 and, as

the jack or jacks having the master butts 40 thereon move upwardly, they will engage the bottoms of the needles in alignment therewith to thus pass the upper ends of the needles adjacent the longest of the wrap yarn guiding fingers 41 which will wrap the yarn thereabout in a conventional manner (Figure 27). The position of the wrap head is clearly shown and described in U. S. Patent Nos. 2,167,390 and 2,206,097.

Now, as the aforesaid jacks 31 having the master butts 40 thereon move beyond the cam 82 in Figure 12, each of the master butts 40 engage a cam 145 which draws the associated jack downwardly to a position which it will retain for the remainder of the revolution of the needle cylinder 11. In the meantime, the butt 32 of each of the needles 33, that had been associated with the jack 31, having the master butt 40 integral therewith, will continue along the dotted lines indicated at 143 in Figure 12 and will engage the lower surface of the alining cam 131 which will draw the needle 33 downwardly and at which time it will pass through a stitch cam group which is secured to the stitch cam block 24 in a conventional manner. These stitch cams are conventional and comprise a front stitch cam 150 (Figure 12), a center guard cam 151, a rear stitch cam 152 and a center raise cam 153. The cam 145 adjacent the front stitch cam 150 and the center raise cam 153, in Figure 12, is secured to the fixed cam plate 102, as by screws 155 (Figure 2).

The stitch cam block 24, having the cams 150 to 153, inclusive, mounted thereon, is mounted for horizontal sliding movement on the vertically movable cam plate 25 and conventional spring means (not shown) normally urge the stitch cam block 24 and its associated cams in such a manner that the associated cams are urged against the periphery of the cylinder 11. The vertically movable cam plate 25 is secured as by screws 160 (Figure 2) disposed in holes 158 and 159 (Figure 10) to the upper end of a bar 161 (Figure 3) which slidably penetrates the base plate 10 and extends downwardly and is curved towards the front of the machine and is secured in a conventional manner at its lower end to a conventional fashion or tightening bracket 163 (Figure 1). The tightening bracket 163 has a plurality of vertically adjustable plungers generally designated as 164 projecting from the lower end thereof which are adapted to individually engage any one of a plurality of cam members 165 secured, in a conventional manner, to a conventional fashion wheel 167 (Figure 1). The fashion wheel 167 is keyed to the shaft 21, in a conventional manner, and a further description of this fashion wheel is not deemed necessary.

In operation, the vertically adjustable plungers 164 are so adjusted as to cause the tightening bracket 163 to be raised upwardly a predetermined amount as the plungers 164 are engaged by the cam members 165 on the fashion wheel 167. Obviously, upon the raising and lowering of the tightening bracket 163, the vertically movable cam plate 25 and its associated cam block 24 will also be raised or lowered, as the case may be, to increase the tautness of the stitches or loops knitted by the needles as the stitch cam block is permitted to move downwardly.

Now, due to the fact that the tautness of the stitches vary during the knitting of the entire length of a stocking blank; that is, for example, the knitting of the ankle portion of the stocking blank would be very taut stitches and the

knitting of the looper course would be very loose, which are the two extremes, and, of course, if a very heavy yarn is used in the knitting of the stocking blank, it will be necessary for the stitch cam block 24 to be raised relatively high in comparison to its optimum operating position. The cam plate, per se, being made in the two sections; namely, the vertically movable cam plate 25, and the fixed cam plate 102 will insure that the selector fingers 17 will remain in proper alignment with the projections 76 on the pattern drum 70. Also, since the fixed cam plate 102 is not affected by raising and lowering of the movable cam plate 25 it is thus insured that the sliding selector bars 15 will always be in alignment with the butts 34 of the jacks 31. The main advantages of the mounting of the movable cam plate 25 in the manner heretofore described are that it will greatly improve the quality of the manufactured product as well as eliminate one of the greatest causes of breakage of various parts associated with the needle cylinder and will minimize vibration of the entire machine. After passing through the stitch group of cams, 150 to 153 inclusive, the butts 32 of the needles 33 ride up and are carried by a conventional rear raise cam 170 on which they are supported during their inactive part of a revolution of the needle cylinder 11.

New cams for effecting adjacent wrap stripes of different yarns

The cams which are incidental to the raising of the wrap needles to a higher than normal position are disposed below the level of the fixed cam plate 102 and consist of a safety cam 175, a jack raising cam 176, a booster cam 177 (Figure 12) and an annular ring 180 (Figures 12 and 27) which is secured, as by a pressed fit, in the bore (not shown) in the circular portion 55 of the base 10. This ring 180 is slotted for reception of the lower portion of the cam 176 (Figure 12) and serves to support the lower ends of jacks 31 having butts 36 integral therewith and to provide smooth engagement of the butts 36 as they move onto cam 176.

The safety cam 175 has an outwardly projecting bar 185 integral therewith (Figure 5) which is secured as by a bolt 186 to a block 187 (Figures 2, 4 and 5) secured, as by screws 188, to the peripheral surface of the fixed cam plate 102. The outer end of the bar 185 is secured as by a screw 189 to the circular portion 55 of the base 10, there being a suitable spacer 189a between the lower surface of the bar 185 and the top of the base 10 and which is slidably penetrated by the screw 189. The jack raising cam 176 has an outwardly projecting bar 190 integral therewith (Figure 5) which is secured as by screws 191 to the plate 107 which is, in turn, secured to the circular portion 55 of the base 10 in the manner heretofore described.

The booster cam 177, like the cams 82 and 84, is mounted in such a manner that it may be moved out of the path of the various butts on the jacks 31. The cam 82 being conventional, a complete description of the same will not be given here except to state the cam 82 is spring pressed against the periphery of the needle cylinder 11 and in the knitting of the heel and toe of a stocking blank, conventional means, not shown, cause the cam 82 to move outwardly away from engagement with the periphery of the needle cylinder 11 as well as out of the path of the master butts 40 on the jacks 31.

The booster cam 177 has an outwardly extending

ing arm 195 integral therewith (Figures 8 and 9) which is mounted for horizontal sliding movement in a guide block 196 secured as by screws 197 to the vertical surface of the jack cam bracket holder 105 heretofore described. The outwardly extending arm 195 has a spring perch 200 thereon, the lower end of which is threadably embedded therein, and to which one end of a tension spring 201 is connected (Figures 8 and 9). The other end of the tension spring 201 is connected to the guide block 196 to thus normally urge the booster cam 177 towards the needle cylinder 11.

The outwardly extending arm 195 has a block 203 secured thereto as by screws 204 and an adjustment screw 205 is threadably mounted in the block 203 and is adapted to engage the outer vertical surface of the jack cam bracket holder 105 to thus adjustably restrict inward movement of the cam 177 relative to the guide block 196.

As heretofore stated, when knitting the heel and toe of a stocking the booster cam 177 must be moved out of the path of travel of the butts 36 of various of the jacks 31 at the same time that the cam 82 is moved out of the paths of the master butts 40 integral with various other of the jacks 31. In order to facilitate this movement of the booster cam 177 out of the path of travel of the outwardly projecting butts 36 integral with various of the jacks 31, a lever arm 210 (Figures 2, 4, 8 and 9), pivotally connected as at 211 to the base 10, engages the surface of the spring perch 200 nearest the needle cylinder 11. The free end of this lever arm 210 is urged, by the spring 201, into engagement with a vertically movable cam block 213 having an inclined surface 214 (Figure 3) which, upon upward movement of the cam block 213, engages and causes the lever arm 210 to move in a counterclockwise direction in Figure 2 thus moving the booster cam 177 out of the path of travel of the outwardly projecting butts 36 integral with various of the jacks 31.

The cam block 213 is adjustably secured to a link member 220 having an elongated slot 221 therein which is slidably penetrated by screws 222 and which, in turn, are threadably embedded in the cam block 213. The link member 220 is mounted for vertical sliding movement in a guide block 225 secured as by a screw 226 to the vertical edge of the base 10. The link member 220 extends downwardly in Figure 4 and has a horizontally bent portion 227 and is then again bent downwardly to form a leg 230 and the lower portion of the same passes downwardly and through suitable guides (not shown) in a conventional bracket 231 so that its lower end bears upon the drum 20 or a cam 233 in alignment with the lower end of the said link 220.

The link member 220 has a diagonal bracing member 235 welded between the horizontally bent portion 227 and the vertical leg 230 and to which one end of a tension spring 237 is connected as at 238 (Figure 4). The other end of the tension spring 237 is connected to a suitable spring perch 240 secured to the conventional fashion bracket 163 (Figure 4) to urge the link member 220 against the drum 20.

The cam 233 on the main drum 20 engages the lower end of the link member 220 in correct timed relation with the operation of the machine thus causing the same to move upwardly and to move the booster cam 177 out of the path of travel of the butts 36 on the lower end of the selector jacks 31. It is to be understood that the cam 84 is drawn out of the path of travel of the butts 37

on the jacks 31 when the jacks 31 are to be raised by the booster cam 177 and the conventional cam 82 in the knitting of the body portion of a stocking.

- 5 As heretofore stated, in the knitting of the instep of the hose, the instep draw cam 130 and associated cams 131 and 132 are raised upwardly. Now, after the instep has been knitted, it is possible that the cam 131 will not move downwardly 10 fast enough to move the butts 32 of the needles 30 downwardly to where they will engage the center guard cam 151 (Figure 12) in which instance some of the jacks 31, having the outwardly projecting butt 36 on the end thereof, may 15 not be moved downwardly after they have moved over the top surface of the booster cam 177 in Figure 12. Consequently, the safety cam 175 is provided and this cam will engage either of the butts 35 or 37 to thus draw the associated jacks 20 31 downwardly to where they will be low enough relative to the cam 176 whereby the outwardly projecting butts 36 will engage the cam 176 for a repeat operation.

In Figures 15 to 18 inclusive, two fabrics are 25 shown which are illustrative of the many that may be formed in accordance with this invention, and which may be taken as representative of the many different ones embodying the invention, and which may be formed by the mechanism 30 hereinbefore disclosed, with the exception that the "Argyle" fabric shown in Figures 16 and 18 will require that a wrapping head of the type disclosed in Figures 24 to 26 inclusive and more 35 fully shown in United States Patent No. 2,230,213, be used in place of single disk wrapping head shown in United States Patent No. 1,702,608, modified by having pairs of long and short fingers as shown in Figures 22, 23 and 31, which would 40 be used for producing fabrics such as shown in Figures 15 and 17, and which has heretofore been described. However, in knitting the "Argyle" pattern shown in Figures 16 and 18 it is necessary that slight modifications be made to the wrapping head shown in United States Patent 45 No. 2,230,213, and these modifications are shown in Figures 24, 25 and 26 of the present invention. A similar structure is also shown in Figures 28, 29, and 30 and its function will be later described.

The wrapping head 250, which is commonly 50 known as the "Argyle" wrapping head, comprises a spindle 251 which is tubular in form at its lower part and serves to support rotatably two plates or disks; an upper disk 252 and a lower disk 253. Each of these disks has attached thereto depending fingers of such length that they extend downwardly to feed the wrap yarns in front of the needles, alternate fingers on one disk extending to one horizontal level and those fingers in between extending to a horizontal level different from the others. The top disk 252 has alternately spaced long fingers 254 adjacent each of which a short finger 254a is mounted and these fingers 254 and 254a are secured to the disk 252 as by screws 255. The lower disk 253 has alternately spaced long fingers 260, adjacent each of which a short finger 261 is disposed and these fingers 260 and 261 are secured as by screws 262 to the bottom disk 253.

The fingers 254 and 254a, which are attached to the upper disk, are drilled at two places for guiding the various wrap yarns therethrough as shown in Figures 24 and 25. The fingers 260 and 261 secured to and depending from the lower disk 253, have wrap yarns threaded through openings 75 at their lower ends only. The fingers 260 and 261

are so arranged as to avoid interference with the longer fingers and their wrap threads as shown in said Patent No. 2,230,213. As further shown and described in said patent, the yarns which are to be wrapped about selected needles are threaded down through eyelets in collars 265 and 266 and those yarns which are to be fed through the fingers 254 and 254a depending from the upper disk 252, pass down through the eyelets and then through the small holes in the fingers themselves. Yarns which are to be fed through the fingers 260 and 261 depending from the lower disk 253 are threaded through the eyelets and then through coinciding elongated annular circumferential openings 267 (Figures 25 and 30) in each of the plates 252 and 253 and then to openings in the ends of each finger 260 and 261.

In order to produce the pattern shown in Figures 16 and 18, the disks 252 and 253 are shogged in opposite directions and throughout an extreme movement of about 180 degrees, the two extremes being shown in Figures 28 and 29, respectively. The wrapping head 250, as shown in Figures 23, 24, and 25, is identical to that shown in the said patent with the exception of the fingers 254, 254a, 260 and 261, and a further description is thus deemed unnecessary.

In the disclosed fabric, hosiery is represented and is here shown as socks. Referring more particularly to Figures 15 and 17, the hose is represented at 270. It is shown in Figure 15 as comprising a top portion 271, a body portion 272, a heel 273 and a toe 274. The heel 273 and the toe 274 are both formed by the usual narrowing and widening operations. The body portion 272 of the hose has straight wrap stripes 275 and 277 of different colors in wales immediately adjacent each other and also has wrap design portions one color being indicated at 280 and the other color being indicated at 281 and also being disposed in immediately adjacent wales. This design portion, comprising the color wrap yarns 280 and 281, is shown by way of illustration, to stress the range of patterning that is possible with this apparatus. Obviously, if so desired, other colors of wrap yarns may be applied in the wales on either side of the wrap yarns 276 and 277 or 280 and 281 inasmuch as the number of wrap yarns that may be used in this apparatus is limited only by the number of wales in the stocking blank and the number of yarn feed fingers on the wrap head, although it is not likely that more than eight different colors of wrap yarns would be used at the same time in any one stocking.

To those familiar with the art, it is obvious that in the knitting of a straight wrap stripe, such as is formed from the wrap yarns 276 and 277 in Figures 15 and 17, none of the butts 34 need be broken away from the main portion of the jacks 31. However, in the instance of making a pattern such as is formed by the wrap yarns 280 and 281, in Figures 15 and 17, it is necessary that the butts 34 be broken away in a manner similar to that shown in Figure 21. It will be noted in Figure 21 that a group of four of the jacks 31 has the outwardly projecting butts 36 at the lower ends thereof and the master butts 40 are broken away from these same jacks 31. This group is indicated at A, in Figure 21, and their function is to raise four of the needles higher than the normal wrap stripe needle height to thus pick up and knit a wrap stripe as indicated by the reference character 281 in Figures 15 and 17.

Now, referring to Figure 12, as the jacks 31 in

this group A move from right to left in Figure 12 the butts 36 would ride on the annular ring 480 and would follow the line indicated by the dotted lines 285 and it is thus seen that the butts 36 would be raised by the cam 176 and, since certain of the selector fingers 17 are moved inwardly, these selector fingers would engage those butts 34 remaining on the jacks 31 and would thus raise the corresponding jacks 31 into alignment with the booster cam 177 which would raise the same upwardly whereby the needle at the upper end of each of the jacks in this group A would pick up the wrap yarn from the guiding fingers 47, in the manner heretofore described; and then the butts 32 on the corresponding needles 30 would engage the cam 131 and would thus move the needles 30 as well as the corresponding jacks 31 downwardly to where the lower edges of the butts 36 would again ride on the annular ring 180.

Referring to Figure 21, there is immediately adjacent the group A of jacks 31, a group indicated at B and the jacks 31 in this group B have the butts 36 broken away; however, the master butt 40 remains an integral part of the jacks in this group B and, in operation, this group of jacks B would raise the needles to the normal height for picking up the wrap yarn 280 in Figures 15 and 17 from the guiding fingers 47a. Inasmuch as these jacks having the master butts 40 integral therewith operate in a conventional manner a further description is not deemed necessary. It is obvious in Figure 1 that although the jacks 31 adjacent those in group B, which are in a group designated at C, have the master butts 40 integral therewith, they will not be raised upwardly by the selector fingers 17 inasmuch as there are no butts 34 integral with the same. The remainder of the jacks shown in Figure 21, and disposed within a group designated at D are repetitive of those shown in the groups A, B and C and therefore a further description of the same is not deemed necessary.

The "Argyle" pattern shown in Figures 16 and 18 is merely shown by way of illustration to further enhance the broad range of patterns that it is possible to make with the present invention. The socks shown in Figure 16, being identical to the socks shown in Figure 15 will bear the same reference characters with the small letter a affixed thereto, with the exception of the wrap stripe pattern, which will be presently described. The jacks 31 for making the "Argyle" pattern shown in Figures 16 and 18 are arranged in a manner such as that shown in Figure 27 and like jacks in Figure 27 being the same as like jacks in Figure 21, a further description will not be given. However, it will be noted that every other one of the jacks 31 in Figure 27 is provided with the outwardly projecting butt 36 at the lower end thereof with the butt 40 being broken away, while each of those in between has the master butt 40 integral therewith and has the outwardly projecting butt 36 broken away. It is thus possible, by the use of the "Argyle" wrapping head 250 and the number of wrapping fingers 254, 254a, 260 and 261 shown in Figures 24 and 25, heretofore described, and by arrangement of the jacks in the manner shown in Figure 27, to produce a pattern such as that shown in Figures 16 and 18 and which is made up of the wrap yarns 290, 291, 292 and 293, it being noted that this produces a pattern in which two colors extend diagonally and in wales immediately adjacent each other on the body portion of the hose.

It will be noted in Figures 28, 29 and 30 that there is shown a wrapping head 250 which is identical to the wrapping head 250 shown in Figures 24, 25 and 26 with the exception that fewer wrapping fingers are shown and this would make a pattern similar to that shown in Figures 16 and 18 but would omit either the wrap yarns 290 and 291 or 292 and 293 thus producing a slightly different pattern. In this instance, the parts shown in Figures 28, 29 and 30 bear the same reference characters as like parts shown in Figures 24, 25 and 26.

In the drawings and specification there has been set forth a preferred embodiment of the invention, and although specific terms are employed, they are used in a generic and descriptive sense only, and not for purposes of limitation, the scope of the invention being defined in the claims.

I claim:

1. In a circular independent needle knitting machine having a needle cylinder with a plurality of vertically movable needles therein and a wrap shaft disposed thereabove in a vertical position but in off-set or eccentric relation to the longitudinal center of the needle circle and having a wrap disk mounted on its lower end provided with a plurality of depending fingers for feeding wrap yarns across the needle circle, said machine having a cam plate provided with a plurality of cams, such as knitting cams and the like, and having means for raising and lowering the cam plate to regulate the tautness of stitch being knitted by the machine, a fixed cam plate substantially surrounding the needle circle and having a plurality of slidable needle selecting bars mounted therein, said needle cylinder having jacks disposed below the needles for cooperation with the selector bars for selecting and raising predetermined needles to take wrap threads, whereby the first cam plate can be raised and lowered to regulate the tautness of the stitch without affecting the elevation of the selector fingers which operate upon the butts of the jacks associated with the needles.

2. In a circular independent needle knitting machine having a needle cylinder provided with a plurality of needles and each needle having a jack associated therewith having prearranged butts and having selecting means comprising slideable cam bars for engaging the butts on certain jacks for raising certain needles to a predetermined height, other means for raising needles adjacent to the previously raised needles to a higher elevation, a wrap shaft disposed above the needle cylinder and mounted eccentrically with relation thereto and having a plurality of pairs of depending fingers extending downwardly therefrom, each finger having a feed eye therein disposed at a different elevation from the feed eye of its associated finger, whereby the lowermost feed eye will deposit its wrap yarn on the needles raised to a predetermined height and the yarns in the feed eyes disposed in a higher elevation will be wrapped around the needles raised to a higher elevation than the first raised needles, whereby different wrap yarns can be wrapped around adjacent needles in the needle circle, a fixed plate on which the selecting means is mounted, said machine also having a vertically movable cam plate for supporting stitch cams and the like with means for raising and lowering the vertically movable cam plate and whereby the vertically movable cam plate can be raised and lowered without affecting the alinement of the butts on the jacks with the selecting means.

3. In a knitting machine having a framework and having a driven needle cylinder and needles with corresponding jacks mounted for vertical sliding movement in the needle cylinder, said 5 jacks having butts thereon, and a pattern drum provided with a plurality of butts and being mounted on the framework of the knitting machine and a group of conventional stitch cams and a group of wrap needle selecting cams, and 10 a group of laterally movable selector fingers responsive to the butts on the pattern drum for engaging certain butts on the jacks for elevating the jacks so as to aline certain jacks with said selecting cams, a cam plate on which the selecting cams and the selector fingers are mounted, means securing said cam plate to the framework of the knitting machine, a vertically movable stitch cam plate disposed substantially in the same horizontal plane as the first named cam 15 plate and on which the stitch cams are mounted, thus permitting movement of the stitch cams relative to the wrap needle selecting cams, and allowing for proper tension on the knitted fabric without affecting alinement of the wrap needle 20 selecting cams and the selector fingers with the butts on the jacks and the butts on the pattern drum.

4. In a circular knitting machine having a needle cylinder in which vertically movable needles and corresponding vertically movable jacks are mounted, a first selecting means, normal cam means for raising first jacks to a proper position for alinement with said first selecting means, said first selecting means being operable to further raise said first jacks to cause said first jacks to raise corresponding first selected needles to a given height above the normal level of the needles and means for presenting a first wrap yarn to said first selected needles for subsequently knitting a wrap stripe; the combination therewith of a second selecting means including other cam means for raising second selected jacks and to thereby raise corresponding second needles immediately adjacent the first selected needles to a higher level than said given height of said first selected needles, means for presenting a second wrap yarn to the second needles as they are raised to said higher level for subsequently knitting, so that two different wrap yarns are 45 knit in immediately adjacent wales of knitted fabric, and means for raising said second jacks into proper alinement with said other cam means associated with the second selecting means.

5. In a structure according to claim 4, some of 55 the said jacks having master butts intermediate their ends and being devoid of butts at their lower ends and said knitting machine having normal supporting means engageable by the master butts for supporting the jacks during that 60 part of a revolution of the needle cylinder in which these jacks are inactive, others of said jacks having butts at their lower ends and being devoid of the master butt, means for supporting the lower ends of the jacks which have the butts 65 at the lower ends thereof during that part of a revolution in which these last-named jacks are inactive.

6. In a circular knitting machine having a driven needle cylinder provided with needles and 70 having corresponding jacks for each of the needles and the needles and the jacks being mounted for vertical sliding movement in the periphery of the cylinder, some of the said jacks having conventional pattern butts integral therewith and conventional jack raising master butts

intermediate their ends but being devoid of butts at their lower ends, said knitting machine having automatically controlled selecting fingers thereon which project into the path of travel of the pattern butts on the jacks, means for directing wrap yarns to the upper end of the needle cylinder in different horizontal planes and said machine having normal cam means to which the last-named jacks are directed from the selecting means for raising these jacks and their corresponding needles to a predetermined given height for engaging a wrap yarn, similar jacks disposed immediately adjacent the jacks having the master butts thereon, the last-named jacks having butts at the lower ends thereof and also having pattern butts integral therewith but being devoid of the master butts, a second cam means, said selecting means engageable by the pattern butts on the last-named jacks for directing the last-named jacks to the second cam means, said second cam means being engageable by the butts at the lower ends of the last-named jacks for raising the last-named jacks and their corresponding needles to a higher elevation than the given height of the first-named jacks for picking up a second wrap yarn whereby two different colors of wrap yarn may be knitted into wales immediately adjacent each other in knitted fabric.

7. In a structure according to claim 6, said knitting machine having a conventional driven cam drum thereon and cam means on the cam drum, a connection between the cam drum and the second cam means for engaging the butts on the lower ends of the last-named jacks for holding the second cam means in position for engagement by the last-named jacks and said cam means on the cam drum being arranged so as to permit the second cam means to move out of the path of the lower ends of the last-named jacks during reciprocatory knitting.

8. In a circular independent needle knitting machine having a needle cylinder with a plurality of vertically movable needles therein, said machine having a cam plate provided with a plurality of cams, such as knitting cams and the like, and having means for raising and lowering the cam plate to regulate the tautness of stitch being knitted by the machine, a fixed cam plate substantially surrounding the needle circle and having a plurality of slideable needle selecting bars mounted therein, said needle cylinder having jacks disposed below the needles for cooperation with the selector bars for selecting and raising predetermined needles whereby the first cam plate can be raised and lowered to regulate the tautness of the stitch without affecting the elevation of the selector fingers which operate upon the butts of the jacks associated with the needles.

9. In a circular independent needle knitting machine having a needle cylinder provided with a plurality of needles and each needle having a jack associated therewith having prearranged butts and having selecting means comprising slideable cam bars for engaging the butts on certain jacks for raising certain needles to a predetermined height, other means for raising needles adjacent the previously raised needles to a higher elevation, a wrap shaft disposed above the needle cylinder and mounted eccentrically with relation thereto and having a plurality of pairs of depending fingers extending downwardly therefrom, each finger having a feed eye therein disposed at a different elevation from the feed eye of its associated finger, whereby the lowermost

feed eye will deposit its wrap yarn on the needles raised to a predetermined height and the yarns in the feed eyes disposed in a higher elevation will be wrapped around the needles raised to a higher elevation than the first raised needles, whereby different wrap yarns can be wrapped around adjacent needles in the needle circle, said machine having a pattern selector drum provided with butts for engaging the selecting means, a fixed plate on which the selecting means is mounted, said machine also having a vertically movable cam plate for supporting stitch cams and the like with means for raising and lowering the vertically movable cam plate and whereby the vertically movable cam plate can be raised and lowered without affecting the alignment of the butts on the pattern drum with the selecting means.

10. In a circular knitting machine having a driven needle cylinder and having vertically movable needles with corresponding jacks mounted in the periphery of the needle cylinder and normal cam means and selecting means for alining selected jacks with the normal cam means for raising corresponding needles to a given height for receiving wrap yarns, feeding means for directing yarns at different elevations adjacent the upper end of the needle circle, a second cam means for selecting other selected jacks disposed immediately adjacent the jacks which are raised to the given height for raising the last-named jacks to a higher elevation, thus raising their associated needles to a higher elevation than the first-raised wrap needles for receiving a wrap yarn from the feeding means to be knitted into the wale immediately adjacent the wale into which the normal wrap yarns will be knitted in a knitted fabric, said knitting machine having a vertically movable instep draw cam and an alining cam disposed in the same horizontal plane, said needles having butts at their lower ends, means rigidly interconnecting the alining and instep draw cams and so arranged as to provide an opening therebetween to permit the butts of the needles which are raised to a higher elevation than the said needles raised to a given height, in picking up a wrap yarn, to pass between the alining and instep draw cams.

11. In a circular knitting machine having a driven needle cylinder and having vertically movable needles with corresponding jacks mounted in the periphery of the needle cylinder and normal cam means and selecting means for alining selected jacks with the normal cam means for raising corresponding needles to a given height for receiving wrap yarns, feeding means for directing yarns at different elevations adjacent the upper end of the needle circle, a second cam means for selecting other selected jacks disposed immediately adjacent the jacks which are raised to the given height for raising the last-named jacks to a higher elevation, thus raising their associated needles to a higher elevation than the first-raised wrap needles for receiving a wrap yarn from the feeding means to be knitted into the wale immediately adjacent the wale into which the normal wrap yarns will be knitted in a knitted fabric, said knitting machine having a vertically movable instep draw cam and an alining cam disposed in the same horizontal plane, said needles having butts at their lower ends, means rigidly interconnecting the alining and instep draw cams and so arranged as to provide an opening therebetween to permit the butts of the needles which are raised to a higher elevation than the said

needles raised to a given height, in picking up a wrap yarn, to pass between the alining and instep draw cams, said knitting machine having means for moving the instep draw cam and the alining cam upwardly during reciprocatory knitting and having automatic means for again moving the instep draw cam and alining cam downwardly at the end of a reciprocatory knitting operation and also having stitch cams to which the butts of the needles are directed by the alining cam while in its lower position during rotary knitting for lowering corresponding jacks, a lowering cam means following the stitch cam and engageable by the jacks which are raised to a higher elevation than the said given height needles in the event that the alining cam does not move downwardly quickly enough upon change from reciprocatory knitting to rotary knitting, for the butts of the needles to engage the said alining cam, a raise cam following the lowering cam and engageable 20 by the lower ends of these jacks whereby the said lowering cam means will move those jacks which remain at a higher elevation than the said given height jacks, in changing from reciprocatory to rotary knitting, downwardly, thereby alining the 25 last-named jacks with the raise cam and, in turn, with the selecting means.

12. In a circular independent needle knitting machine provided with a needle cylinder having a plurality of vertically movable needles and having jacks with butts associated therewith, said machine also having stitch cams and said machine having jack selecting means including selector fingers and selector cams; a fixed member on which the jack selecting means is mounted, and a vertically movable cam plate mounted on the machine and on which said stitch cams are mounted so as to permit relative vertical movement between the jack selecting means and the stitch cams without affecting the relationship between the selector fingers and the selector cams 15 and the butts on the jacks.

MARVIN R. BRYANT.
